UNITED STATES PATENT OFFICE.

ROBERT KLINE, OF CLEVELAND, OHIO, ASSIGNOR TO THE B-O-C. MFG. CO., OF CLEVELAND, OHIO.

DESIGN FOR A SAVINGS-BANK.

46,531.

Specification for Design.

Patented Oct. 13, 1914.

Application filed July 16, 1914. Serial No. 851,412. Term of patent 3½ years.

To all whom it may concern:

Be it known that I, ROBERT KLINE, a citizen of the United States, residing at Cleveland, in the county of Cuyahoga and State of Ohio, have invented a new, original, and ornamental Design for Savings-Banks, of which the following is a specification, reference being had to the accompanying drawing, forming part thereof.

bank showing my new design. Fig. II is a rear perspective view of the same.

I claim:

The ornamental design for a savings bank as shown.

ROBERT KLINE.
